FRANK J. KRISTOFER, OF ST. PAUL, MINNESOTA, ASSIGNOR TO BROWN & BIGELOW,
OF ST. PAUL, MINNESOTA, A CORPORATION OF MINNESOTA.

BOTTLE-CAP REMOVER.

1,278,684.

Specification of Letters Patent. Patented Sept. 10, 1918.

Application filed May 17, 1917. Serial No. 169,352.

To all whom it may concern:

Be it known that I, FRANK J. KRISTOFER, a citizen of the United States, residing at St. Paul, in the county of Ramsey and State 5 of Minnesota, have invented a new and useful Improvement in Bottle-Cap Removers, of which the following is a specification.

This invention relates to a bottle cap remover in which a simple device is provided 10 for quickly removing paper cap stoppers from dairy bottles.

The primary object is in providing a device formed from a single piece of material having a piercing element and spring 15 engaging plates which prevent the disengagement from the engaging plates when the device is in use.

A further object is in providing engaging plates which assume a wedge shaped gripping member when pressed between the fingers of the user, so that the bottle cap can be easily pulled or disengaged from the bottle. When the pressure is released on the engaging plates or sides, they will expand 25 to normal position.

It is also an object to provide stiffening and strengthening means in the piercing element so as to prevent the same from bending or easily breaking when in use.

30 In the drawing which forms part of this specification:

Figure 1 is a perspective of the bottle cap remover.

Fig. 2 is a side elevation of the cap re- 35 mover.

Fig. 3 illustrates the cap remover in use.

In the drawing, A represents a bottle cap 40 remover formed from thin sheet spring metal or other suitable material, by stamping the same with a die. The sheet 1 is bent U shaped so as to form engaging plates 2 and 3 which lie normally parallel to each other. Forming the remover A from spring material 1 allows the plates 2 and 3 to be 45 pressed together easily and to return again to normal position parallel to each other.

The cap remover has an arrow shaped piercing element 4 formed with a central longitudinally disposed stiffening rib 5.

50 The piercing element 4 is connected to the free edge of the plate 2 by a shank 6, and the stiffening rib 5 is adapted to extend centrally through the shank 6 to stiffen and strengthen the same. Thus the rib 5 tends 55 to hold the piercing element 4 with its con-

necting shank 6 against bending or breaking when in use.

The piercing element 4 is formed with a sharp point 7 and shoulders 8 on the rear portion of the same, which are adapted to 60 engage the bottle cap 9 when the cap remover A is in use. It is not always necessary to force the piercing element through the paper cap 9 to remove the same, but if it is desired, the cap can be pried off by 65 piercing the same with the sharp point 7 and then prying upward with the piercing element, thereby easily removing cap 9.

In forming or stamping the cap remover A from the thin sheet material 1, the usual 70 bur edge 10 is formed about the engaging plates 2 and 3. To prevent extra labor of removing the same, the plates 2 and 3 are bent so as to have the bur edge 10 turned toward the inside, as is illustrated in Fig. 75 2. This construction prevents the danger of cutting the fingers of the user on the cap remover A on the bur edge of the plates 2 and 3. For convenience a hole 11 is formed in the plate 2 so that the cap remover A 80 can be hung in any convenient place in the kitchen, as is the case with other kitchen utensils.

In use, the bottle cap remover A is held 85 between the thumb, index and middle fingers, and the piercing element 4 formed through the bottle cap 9. The remover 9 is then turned quarter turn on the shank 6 and pulled upward by the fingers, which automatically causes pressure of the fingers 90 against the engaging plates 2 and 3, compressing the same to form a wedge shaped gripping member. By means of the wedge shaped spring gripping member formed by the plates 2 and 3, it is not necessary to exert 95 a large amount of pressure on the plates 2 and 3 when pulling on the same to prevent the fingers from slipping off the engaging plates, as the case would be if the engaging plates were rigidly held parallel to each other. In fact, the harder the pull on the engaging plates 2 and 3, the more the pressure to compress the same will be, and plates 2 and 3 automatically compress until their free ends touch each other, thereby 100 forming the wedge shaped gripping member between the finger tips of the user.

The plates 2 and 3, as shown, are rectangular in shape but it is obvious that they 110 can be made circular or in any other suit-

able form or shape to accomplish the same results. It is also evident that the piercing element 4 can be of a different shape.

It is an important feature to provide an inexpensive article which can be used for removing paper bottle caps in a convenient way without danger of spilling the contents of the bottle.

While I have illustrated one particular form of device, I desire to have it understood that I do not wish to confine myself to this particular construction but that the invention can be carried out by other means and applied to other uses within the scope 15 of the following claims:—

1. In a bottle cap remover comprising engaging plates formed from a single piece of thin sheet material bent U shape, said plates being substantially rectangular in shape and 20 extending parallel to each other, a piercing element formed with and projecting centrally from the free edge of one of said plates, a shank connecting said piercing ele-

ment with said plate from which it projects, said shank being of less width than the rear end of said piercing element and a wedge-shaped stiffening rib formed in and extending from the point of said piercing element through the connecting shank to the plate carrying said piercing element.

2. In a bottle cap remover comprising engaging plates stamped from a single piece of sheet material, said sheet material being bent U shape to cause said plates to lie parallel to each other with the stamping bur on the edge of said plates extending inwardly, a wedge-shaped piercing element, a shank of less width than the rear end of said piercing element and a wedge-shaped stiffening rib formed centrally through said piercing element and shank, said rib increasing in width and depth from the point of said piercing element to the head or rear of said piercing element and plate to which said piercing element is connected.

FRANK J. KRISTOFEK.
